US00D852304S

(12) **United States Design Patent** (10) **Patent No.:** **US D852,304 S**
Parsons et al. (45) **Date of Patent:** **** Jun. 25, 2019**

(54) **GOLF CLUB HEAD**
(71) Applicant: **PARSONS XTREME GOLF, LLC**,
Scottsdale, AZ (US)
(72) Inventors: **Robert R. Parsons**, Scottsdale, AZ
(US); **Bradley D. Schweigert**, Anthem,
AZ (US); **Michael R. Nicolette**,
Scottsdale, AZ (US)
(73) Assignee: **PARSONS XTREME GOLF, LLC**,
Scottsdale, AZ (US)
(**) Term: **15 Years**
(21) Appl. No.: **29/661,161**
(22) Filed: **Aug. 24, 2018**

Related U.S. Application Data

(63) Continuation-in-part of application No. 29/656,913, filed on Jul. 17, 2018, now abandoned, which is a continuation-in-part of application No. 29/646,582, filed on May 4, 2018, now abandoned, application No. 29/661,161, which is a continuation-in-part of application No. 29/646,576, filed on May 4, 2018, now abandoned, which is a continuation-in-part of application No. 29/645,048, filed on Apr. 23, 2018, now abandoned.

CLAIM

The ornamental design for a golf club head, as shown and described.

DESCRIPTION

FIG. 1 is a top perspective view of a golf club head;
 FIG. 2 is a bottom perspective view of the golf club head of FIG. 1;
 FIG. 3 is a front elevational view of the golf club head of FIG. 1;
 FIG. 4 is a rear elevational view of the golf club head of FIG. 1;
 FIG. 5 is a top view of the golf club head of FIG. 1;
 FIG. 6 is a bottom view of the golf club head of FIG. 1;
 FIG. 7 is a left side view of the golf club head of FIG. 1;
 FIG. 8 is a right side view of the golf club head of FIG. 1;
 FIG. 9 is a top perspective view of a second embodiment of a golf club head;
 FIG. 10 is a bottom perspective view of the golf club head of FIG. 9;
 FIG. 11 is a front elevational view of the golf club head of FIG. 9;
 FIG. 12 is a rear elevational view of the golf club head of FIG. 9;
 FIG. 13 is a top view of the golf club head of FIG. 9;
 FIG. 14 is a bottom view of the golf club head of FIG. 9;
 FIG. 15 is a left side view of the golf club head of FIG. 9;
 FIG. 16 is a right side view of the golf club head of FIG. 9;
 FIG. 17 is a top perspective view of a third embodiment of a golf club head;
 FIG. 18 is a bottom perspective view of the golf club head of FIG. 17;
 FIG. 19 is a front elevational view of the golf club head of FIG. 17;
 FIG. 20 is a rear elevational view of the golf club head of FIG. 17;
 FIG. 21 is a top view of the golf club head of FIG. 17;
 FIG. 22 is a bottom view of the golf club head of FIG. 17;
 FIG. 23 is a left side view of the golf club head of FIG. 17;
 FIG. 24 is a right side view of the golf club head of FIG. 17;

FIG. 25 is a top perspective view of a fourth embodiment of a golf club head;
 FIG. 26 is a bottom perspective view of the golf club head of FIG. 25;
 FIG. 27 is a front elevational view of the golf club head of FIG. 25;
 FIG. 28 is a rear elevational view of the golf club head of FIG. 25;
 FIG. 29 is a top view of the golf club head of FIG. 25;
 FIG. 30 is a bottom view of the golf club head of FIG. 25;
 FIG. 31 is a left side view of the golf club head of FIG. 25;
 FIG. 32 is a right side view of the golf club head of FIG. 25;
 FIG. 33 is a top perspective view of a fifth embodiment of a golf club head;
 FIG. 34 is a bottom perspective view of the golf club head of FIG. 33;
 FIG. 35 is a front elevational view of the golf club head of FIG. 33;
 FIG. 36 is a rear elevational view of the golf club head of FIG. 33;
 FIG. 37 is a top view of the golf club head of FIG. 33;
 FIG. 38 is a bottom view of the golf club head of FIG. 33;
 FIG. 39 is a left side view of the golf club head of FIG. 33;
 FIG. 40 is a right side view of the golf club head of FIG. 33;
 FIG. 41 is a top perspective view of a sixth embodiment of a golf club head;
 FIG. 42 is a bottom perspective view of the golf club head of FIG. 41;
 FIG. 43 is a front elevational view of the golf club head of FIG. 41;
 FIG. 44 is a rear elevational view of the golf club head of FIG. 41;
 FIG. 45 is a top view of the golf club head of FIG. 41;
 FIG. 46 is a bottom view of the golf club head of FIG. 41;
 FIG. 47 is a left side view of the golf club head of FIG. 41;
 FIG. 48 is a right side view of the golf club head of FIG. 41;
 FIG. 49 is a top perspective view of a seventh embodiment of a golf club head;
 FIG. 50 is a bottom perspective view of the golf club head of FIG. 49;
 FIG. 51 is a front elevational view of the golf club head of FIG. 49;
 FIG. 52 is a rear elevational view of the golf club head of FIG. 49;
 FIG. 53 is a top view of the golf club head of FIG. 49;
 FIG. 54 is a bottom view of the golf club head of FIG. 49;
 FIG. 55 is a left side view of the golf club head of FIG. 49;
 FIG. 56 is a right side view of the golf club head of FIG. 49;
 FIG. 57 is a top perspective view of an eighth embodiment of a golf club head;
 FIG. 58 is a bottom perspective view of the golf club head of FIG. 57;
 FIG. 59 is a front elevational view of the golf club head of FIG. 57;
 FIG. 60 is a rear elevational view of the golf club head of FIG. 57;
 FIG. 61 is a top view of the golf club head of FIG. 57;
 FIG. 62 is a bottom view of the golf club head of FIG. 57;
 FIG. 63 is a left side view of the golf club head of FIG. 57;
 and,
 FIG. 64 is a right side view of the golf club head of FIG. 57.
 The broken line showing is included for the purpose of illustrating unclaimed subject matter and forms no part of the claimed design.
